UNITED STATES PATENT OFFICE.

JOHN V. CUNNIF, OF FALL RIVER, MASSACHUSETTS, ASSIGNEE TO WILLIAM E. DRAPER, OF HOPEDALE, MASSACHUSETTS.

SPINNING-SPINDLE.

942,777.

Specification of Letters Patent. Patented Dec. 7, 1909.

Application filed June 21, 1909. Serial No. 503,299.

To all whom it may concern:

Be it known that I, JOHN V. CUNNIF, a citizen of the United States, residing at Fall River, in the county of Bristol and State of Massachusetts, have invented an Improvement in Spinning-Spindles, of which the following description, in connection with the accompanying drawings, is a specification, like figures on the drawings representing like parts.

The invention to be hereinafter described relates to spinning spindles and more particularly to the means for operatively connecting the bobbins to said spindles to cause the former to rotate therewith.

The aims and purposes of the invention are to provide simple and efficient means whereby a bobbin placed upon the spindle of a spinning machine may be effectively connected to the spindle at the upper portion thereof, all as will more fully appear from the following description and accompanying drawings of one form of means for carrying the invention into practical effect.

In the drawings: Figure 1 is a sectional and side elevation of a bobbin and spinning spindle showing the manner of supporting the bobbin in driving relation with the spindle; Fig. 2 is a plan view looking down upon the end of the spindle, shown in Fig. 3; and Fig. 3 is a detailed view of a modified form of spindle showing only the top portion thereof.

Having reference to Fig. 1, the spindle 1 is shown as provided with a lower portion 2 to engage a suitable sustaining bearing, as usual, and provided with a whirl 3 by which the spindle may be driven from any suitable source of power. Above the whirl 3 the spindle is or may be provided with an enlarged portion, as 4, terminating at its upper end in a seat 5 for the lower end of a bobbin 6, said bobbin having a sustaining shoulder 7. Above the seat 5 the spindle 1 is preferably formed tapering, as at 8, to receive the correspondingly shaped lower bored portion 9 of the bobbin 6, the construction being such that the bobbin 6 may be pushed down on the spindle so that the shoulder 7 may be seated on the seat 5, to enable all the bobbins in a spinning frame to be sustained at the same height or level, if desired, though with respect to other features of the spindle structure these details may vary. It will be observed that

the tapered portion 8 does not fit snugly the lower bored portion 9, so as to cause frictional engagement, thus leaving, as is intended, the sole bobbin driving connection between the spindle and bobbin at the top. 60

At its upper portion the spindle 1 is formed with spring fingers 10 preferably provided by a cut 11 extending longitudinally of the spindle, the top portions 12 of the spring fingers 10 being preferably beveled or slanting downward and outward in order that the spring fingers may readily be contracted as the upper bearing portion 13 of the bobbin 6 is moved down and about said spring fingers when the bobbin is placed upon the spindle. 65

From the construction described it will be noted that the upper end portion of the spindle is provided with integrally formed spring fingers which engage the bore of the bobbin at its upper portion and constitute the driving connection between the bobbin and spindle. Obviously the spring fingers may vary in number and kind, as indicated in Figs. 2 and 3, wherein there are four 70 spring fingers 10', formed by intersecting cuts 11'.

The character of the spindle may be varied as to its supporting bearing, its driving means, manner of defining the vertical position of the bobbin thereon, and other details, the true scope of the invention being defined by the claims:

What is claimed is:

1. A spinning spindle having spring fingers at its upper portion formed integral therewith and forming the sole bobbin driving connection between the spindle and bobbin. 80

2. An upright spinning spindle having a slot at its upper portion forming spring bobbin-driving fingers adapted to engage the interior of and drive a bobbin and having a shoulder or seat for the lower part of the bobbin, said spring fingers forming the sole bobbin driving connection between the bobbin and the spindle. 95

3. A spinning spindle having a projecting portion upon which the lower portion of a bobbin may rest, and provided with bobbin driving spring fingers at its upper portion formed integral with the spindle and forming the sole bobbin driving connection between the bobbin and spindle. 105

4. A spinning spindle having spring 110

fingers at its upper portion formed integral therewith, the ends of said spring fingers having inclined surfaces and a seat or shoulder on the spindle on which the lower end 5 of the bobbin may rest, said spring fingers forming the sole bobbin driving connection between the bobbin and the spindle.

In testimony whereof, I have signed my name to this specification, in the presence of two subscribing witnesses.

JOHN V. CUNNIFF.
